[57] CLAIM

The ornamental design for an end standard for a vehicle
seat or similar article, as shown and described.

DESCRIPTION

FIG. 1 is a side elevational view of an end standard for
a vehicle seat or similar article, showing my new design;
FIG. 2 is an elevational view, showing the side not
shown in FIG. 1;

FIG. 3 is a cross sectional view, taken along line 3—3 in
FIG. 2;

FIG. 4 is a cross sectional view, taken along line 4—4 in
FIG. 2;

FIG. 5 is a top plan view; and

FIG. 6 is a bottom plan view thereof.

FIG. 1

FIG. 2

FIG. 3

FIG. 4

FIG. 5

FIG. 6
